(57) **CLAIM**

The ornamental design for a vehicular roof plate, as shown and described.

DESCRIPTION

FIG. 1 is a top, right, rear perspective view of the vehicular roof plate of my design;

FIG. 2 is a bottom, perspective view thereof;

FIG. 3 is a rear elevation view thereof;

FIG. 4 is a front, elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is a top perspective view illustrating the vehicular roof plate affixed to the corrugated roof of a vehicle supporting emergency response vehicle identification characters.

The broken lines shown represent unclaimed subject matter and form no part of the claimed design. Specifically, the bolt holes shown in FIGS. 1, 2, 7 and 8; bolts shown in FIGS. 3, 4, 5, 6 and 9; and emergency response vehicle, light bar, antenna and identification characters shown in FIG. 9 are shown for illustrative purposes and form no part of the claimed design.
